(57) **CLAIM**

The ornamental design for a light fixture, as shown and described.

DESCRIPTION

FIG. 1 is a bottom perspective view of a light fixture in accordance with my design;

FIG. 2 is a side elevation view of the light fixture in accordance with my design, the opposite side being a mirror image of that shown;

FIG. 3 is a front elevation view of the light fixture in accordance with my design, the opposite side being a mirror image of that shown;

FIG. 4 is a top plan view of the light fixture in accordance with my design; and,

FIG. 5 is a bottom plan view of the light fixture in accordance with my design.

The light fixture of FIGS. 1-3 is shown with a portion broken away to indicate indeterminate length.
